CHARLES S. LEWIS, OF ST. LOUIS, MISSOURI

PUMP-PRIMING MECHANISM

Application filed May 7, 1928. Serial No. 275,631.

This invention relates to a pump priming mechanism, and is an improvement on the pump priming mechanism described in my prior United States Patent No. 1,080,917, dated December 9, 1913.

The mechanism described in my said patent comprises two chambers arranged at different levels and adapted to receive a liquid, a supply pipe leading to the lower chamber 10 from a pool of liquid, or from a space in which it is desired to create a vacuum, a discharge pipe leading from the upper chamber, a centrifugal or rotary pump arranged with its intake communicating with the lower 15 chamber and its outlet communicating with the upper chamber and adapted to withdraw liquid from the lower chamber, so as to produce a minus pressure in same and in the supply line, and a means for permitting a relatively lesser volume of liquid to flow from the upper chamber into the lower chamber 20 than the volume of liquid which the pump is capable of withdrawing from the lower chamber during a given period, thus causing a partial vacuum or diminution of pressure in the lower chamber to which the supply line leads. When the mechanism is to be used for pumping liquid from a source of supply, it is rendered operative by introducing sufficient 25 liquid into the upper chamber, into the lower chamber, into the intake of the pump, into the impeller chamber of the pump, and into the discharge of the pump to completely fill said elements. The pump is then set in operation, whereupon the liquid in the lower chamber will be drawn out of same and forced 30 into the upper chamber, thus causing an equal volume of liquid to be forced out of the upper chamber through the discharge pipe 35 leading from the same. The minus pressure that is created in the lower chamber by the withdrawal of the liquid from said chamber will produce a suction in the supply line that causes liquid from the source of supply 40 to rise in said supply line, or flow through said line a greater or less degree, according to the suction that is exerted on the supply line by the withdrawal of the liquid from the lower chamber. After the charge of 45 liquid in the lower chamber has been with-

drawn from same, as previously described, liquid starts to flow into said lower chamber from the upper chamber, so as to provide the lower chamber with another charge of liquid which the pump removes from said lower chamber during the second cycle of operations, so as to again create a minus pressure in the lower chamber, and cause the liquid in the supply line to rise still higher in said line. These cycles are repeated until a continuous column of liquid has been established between the source of liquid supply and the impeller of the pump, after which liquid will be withdrawn continuously from the source of supply and forced through the discharge 55 pipe leading from the upper chamber of the mechanism. When the mechanism is in operation it is necessary that the pump remain air bound or in such a condition that it will not withdraw liquid from the lower 60 chamber during that portion of the first cycle in which liquid is passing from the upper chamber into the lower chamber, for if the pump should continue to withdraw liquid from the lower chamber during the operation 65 of filling said chamber, it would be impossible for enough liquid to collect in the lower chamber to form a charge that will produce the required minus pressure in the lower chamber when said charge is withdrawn from said chamber during the second 70 cycle.

In the commercial use of the mechanism described in my said prior patent it sometimes happened that the pump would not remain air bound at the completion of the operation of withdrawing liquid from the lower chamber, with the result that the lower chamber would not become filled with a full charge of liquid, or with a charge of sufficient 80 volume to insure the mechanism functioning properly. This was due to the fact that liquid would become trapped in the lower end of the U-shaped air pipe which is attached to the intake of the pump and to the lower chamber, which trapped liquid would prevent sufficient air from passing through said air pipe into the intake of the pump to cause the pump to remain in an air bound condition, and thus entirely cease to with- 85 90 95 100

draw liquid from the lower chamber during the operation of filling said chamber.

One object of my present invention is to remedy the above described defect of a pump priming mechanism of the general type described in my said prior patent, and to this end I have provided the mechanism with a connection between the intake of the pump and the lower chamber which is of such construction and arrangement that liquid cannot become trapped in same, and thus interfere with the free flow of air into the intake of the pump that is relied upon to maintain the pump in an air bound condition during that portion of the cycle when the lower chamber is being filled with liquid. Said connection is also so constructed and arranged that it interposes a body or quantity of liquid between the upper part of the lower chamber and the pump intake, during that part of the cycle when the pump is drawing liquid from said lower chamber, the object being to prevent air or gas, which may at that moment be present in the upper part of said lower chamber, from entering the pump and interrupting the flow of liquid into the pump. However, the construction is such that said interposed body of liquid will drain into the intake of the pump after the liquid in the lower chamber has been withdrawn by the pump.

Another thing that sometimes occurs under some operating conditions with a mechanism of the kind described in my said prior patent, is that air becomes trapped between the impeller of the pump and the level of the liquid in the intake of the pump during the operation of filling the lower chamber, thus causing the pump to lag or falter before starting to withdraw liquid from the lower chamber, due, of course, to the fact that the slug of air in the intake prevents the liquid in the intake from freely entering the impeller chamber of the pump. Accordingly, I propose to connect the intake of the pump with the upper chamber of the mechanism in such a manner that air which becomes trapped in the pump intake between the surface of the liquid in the intake and the impeller chamber of the pump, during the operation of filling the lower chamber, will be positively expelled from the intake of the pump at the completion of the operation of filling the lower chamber, thereby effectively eliminating the pump remaining in an air bound condition at a time when the pump is expected to withdraw a charge of liquid from the lower chamber, to create a minus pressure in said chamber.

Another object of my present invention is to provide a pump priming mechanism of the general type referred to, with a means for preventing air from collecting in the intake of the pump and interfering with the operation of the pump after a continuous column

of liquid has been established between the source of supply and the impeller of the pump.

And still another object of my present invention is to provide an improved means for permitting air to pass from the lower chamber into the upper chamber during the operation of filling the lower chamber with liquid, and for preventing liquid from being siphoned out of the apparatus back to the source of supply, due to air entering the apparatus while the pump is not in operation. Other objects and desirable features of my invention will be hereinafter pointed out.

The figure of the drawings is a vertical sectional view of a pump priming mechanism embodying my present invention.

Said mechanism is similar in general design to the mechanism described in my said prior patent previously referred to, in that it comprises two chambers A and B of unequal capacity adapted to hold a liquid and arranged so that the large chamber A is located at a higher level than the small chamber B, a centrifugal or rotary pump D, an inlet C for said pump communicating at one end with the impeller chamber of the pump and at its opposite end with the lower portion of the chamber B, an outlet E leading from the pump D to the chamber A, preferably to the upper portion of said chamber A, a discharge pipe F leading from the upper end of the chamber A, a supply line or vacuum line I that leads to the lower chamber B, and means for permitting liquid to pass from the upper chamber A into the lower chamber B, so as to fill said lower chamber, after the pump has withdrawn a charge of liquid from said lower chamber to create a minus pressure in same.

My improved apparatus herein described is distinguished, however, in numerous respects from the apparatus described in my said prior patent. For example, it is equipped with a regulator or timer of novel construction for maintaining the pump D in an air bound condition after a charge of liquid has been withdrawn from the lower chamber, and for preventing said pump from resuming the delivery of liquid to the chamber A until after the lower chamber B has been purged of air or gas and filled with another charge of liquid; it is provided with a conduit or other suitable passageway leading from the intake of the pump to the upper chamber A through which any air that has become trapped in the pump intake will be expelled from same at the completion of the operation of filling the lower chamber with liquid; it is provided with a conduit or other suitable passageway leading from the supply line to the intake of the pump, so as to cause liquid to be supplied continuously to the pump intake after a column of liquid has been established between the source of

supply and the impeller of the pump, thereby preventing air from collecting in the intake of the pump and interfering with the operation of the pump, and it is provided with a 5 means of novel construction for permitting air to pass from the lower chamber into the upper chamber during the operation of filling the lower chamber, and for admitting air to the supply line, thus preventing the 10 liquid in the apparatus being siphoned out of same, in the event air leaks into the apparatus at a time when the pump is idle or not in operation. Moreover, my improved apparatus herein described is of such design 15 that no check valves are required between the supply line or vacuum line and the lower chamber B.

As illustrated in the drawing, the discharge pipe F leading from the upper end of the chamber A is provided with a check valve 20 G that permits liquid, gas or air to escape from the chamber A through the discharge pipe F, but effectively prevents liquid or air from returning to said chamber through said 25 discharge pipe. The supply line I leads from a vessel, chamber, well, pool or sump L that may either be above the level or below the level of the chambers A and B, said supply line being herein illustrated as arranged 30 with its lower end submerged in a pool of liquid L located at a lower level than the bottom of the chamber B and leading upwardly from said pool to a horizontal portion I' of the supply line that is arranged at a 35 higher level than the top of the chamber A. This horizontal portion I' of the supply line communicates with an upright portion I² of the supply line that leads downwardly to the chamber B, it being essential that the 40 portion I' be located at the same or at a higher level than the chamber A, in order to prevent back flow of the liquid to the pool L by gravity. Said upright portion I² may either be disposed vertically or at an angle, 45 but when the large chamber A is superimposed upon the small chamber B, as herein illustrated, it is preferable to have the portion I² of the supply line extend downwardly through the chamber A, as shown in the 50 drawing.

The regulator or timer, previously referred to, that constitutes one of the novel features of my present invention, is positive in its action, as it operates by both gravity and pressure differential. It comprises a small receptacle K arranged entirely or partly within the upper portion of the lower chamber B, or arranged outside of said chamber and connected by a pipe with the interior of the 55 upper portion of said chamber. Said receptacle K, when arranged within the chamber B, is open at its upper side and is connected by a downwardly inclined pipe or small duct M with the intake C of the pump. This duct 60 M is used to introduce liquid into the intake 65 C of the pump from the receptacle K during the operation of filling the lower chamber B with liquid, and is so proportioned in cross sectional area that the receptacle K is not emptied of liquid until after the liquid in 70 the lower chamber B has been withdrawn by the pump D, thereby eliminating the possibility of the flow of liquid from the chamber B ceasing or being interrupted by air or gas which may be present in the upper part 75 of the chamber B passing into the pump intake C until after the entire charge of liquid has been withdrawn from said chamber. Said duct is also used to permit the liquid to pass from the intake C of the pump into the receptacle K during the operation of filling the chamber B. The duct M is also used in 80 conjunction with the receptacle K to form a connection between the intake of the pump and the upper portion of the chamber B through which air will pass into the intake of the pump, and thus insure the pump remaining air bound during the operation of filling the lower chamber B with liquid.

Communication is established between the chamber A and the chamber B by a by-pass or connection N through which liquid passes from the chamber A to the chamber B. Communication is also established between said chambers by a pipe O arranged with one of its ends terminating inside of the outlet pipe E of the pump and its other end communicating with or terminating inside of the upper end of the depending portion I² of the supply line. Preferably, the pipe N is provided with a valve or other suitable means N' for regulating or entirely stopping the flow of liquid from the chamber A to the chamber B through the pipe N, and the pipe O is provided with a valve or other suitable means O' for regulating or entirely stopping the flow of liquid through said pipe O. In order that the various chambers, pipes, 95 ducts and connections of the apparatus may be filled conveniently with a priming liquid, a filling pipe P equipped with a stop valve P' is attached to the upper end of the portion I² of the supply line.

The conduit or passageway previously referred to that is used to permit the escape of air that becomes trapped in the pump intake between the impeller chamber of the pump and the level of the liquid in the intake is herein illustrated as being formed by a pipe R that leads from the pump intake C to the chamber A preferably below the point of the lowest liquid level attained in the chamber A, said pipe being preferably equipped with a suitable valve or regulating device R'.

The conduit or passageway previously referred to that is used to supply liquid to the intake of the pump so as to prevent air from collecting in the intake, and thus interfering with the operation of the pump, after a column of liquid has been established between 125

the source of supply and the impeller of the pump, is herein illustrated as being formed by a pipe S that leads from the horizontal portion I' of the supply line to the pipe M that enters the intake C of the pump, said pipe S being preferably equipped with a suitable regulating or controlling valve S'. Before the apparatus is set in operation water or any other suitable liquid is introduced through the filling pipe P, so as to fill the lower chamber B, the pump intake C and pump D, the pipe M and receptacle K, the upper chamber A, the intake portion of the discharge pipe F located below the check 10 valve G, the outlet E of the pump, the pipes R and S, and the connection O between the outlet of the pump and the vertical portion I² of the supply line. The air or gas that is expelled from said chambers, ducts and pipes 15 by the entrance of the priming liquid into the same escapes through the valve G into the portion of the discharge pipe F located above said check valve. The apparatus is now in readiness to commence the first cycle which 20 is started by setting the pump D in operation, at the proper rate of rotation, so as to cause the charge of liquid in the chamber B to be withdrawn from said chamber through the inlet C of the pump, and forced upwardly 25 through the outlet E into the chamber A, thereby causing an approximately equal quantity of liquid to be forced out of the chamber A into the discharge pipe F. During this period of the first cycle a relatively 30 lesser quantity of liquid is returned to the chamber B through the by-pass N and through the pipe O, some liquid also passing into the inlet C of the pump, through the pipe R. The combined quantity of liquid 35 that is returned to the chamber B in a given time is less than the quantity of liquid that the pump simultaneously withdraws from said chamber B through the inlet C. Consequently, the operation of withdrawing the 40 charge of liquid from the chamber B produces a minus pressure in said chamber and in the supply line I, with the result that the liquid in the pool L will rise in the supply line I to a height depending upon the pressure differential in the chamber B, in the intake portion of the supply line I² and at the surface of the pool L. Liquid continues to 45 flow into the lower chamber B and pump intake C through the various ducts, pipes or passageways provided for this purpose, and during this period in the cycle liquid is 50 draining out of the receptacle K into the pump intake through the downwardly inclined duct M. After the receptacle K has been emptied of liquid, any air or gas contained in the upper part of the chamber B will escape from said chamber through the receptacle K and pipe M into the upper part of the inlet C of the pump, thus unifying the pressure in the chamber B and pump inlet

C, and causing the liquid in the inlet C of the pump to descend to the level of the liquid in the chamber B. Due to the fact that the upper portion of the inlet C of the pump is now filled with air or gas, the pump D will be effectively maintained in an air bound condition, and consequently, cannot resume the withdrawal of liquid from the chamber B, thus insuring said chamber being filled with a charge of liquid of the proper volume. At this period in the cycle, i. e., after the flow of liquid from the pump C has ceased, the air or vapor pressure in the chambers A and B, in the receptacle K, in the pump inlet C and outlet E, in the supply line I and in the ducts R and O becomes uniform or equalized through the pipe O, because the end of said pipe O which terminates inside of the discharge E of the pump is no longer submerged and sealed with liquid, and the liquid previously contained in said pipe O has drained out of same into the vertical portion I² of the supply line. Moreover, at this period of the cycle the chamber B is partly filled with air or gas which has passed into it from the space in the vertical portion I² of the supply line between the surface of the liquid in the pool L, and the chamber B, and said chamber B is partly filled with liquid which returned to it through the various devices provided for this purpose. As the impeller chamber of the pump D is partly filled with air or gas at this period of the cycle, said pump cannot withdraw liquid from the chamber B, and as the air or gas pressure in the chambers A and B is uniform, the liquid in the chamber A will descend by gravity into the chamber B and pump intake through the by-pass N and pipe R, thus gradually filling the chamber B, the receptacle K, the pump inlet C and part of the vertical portion I² of the supply line. As the liquid descends from the chamber A to the chamber B and gradually fills said chamber B, the air or gas which at this time is in the chamber B, receptacle K and pump inlet C, escapes through the pipes M, S, vertical portion I² of the supply line, and pipe O, said air entering the upper portion of the chamber A above the level of the liquid in the same. When the level of the liquid in the chamber B and the pump inlet C rises to the point where the pipe M is attached to the inlet C, the remaining air or gas in the chamber B escapes through the vertical portion I² of the supply line, and thence through the pipe O and outlet E of the pump, into the chamber A, and when the chamber B and receptacle K are completely filled with liquid, the air or gas in the upper part of the pump inlet C escapes upwardly through the pipe R into the chamber A. At this moment there is a continuous body of liquid extending from the chambers A and B into the impeller chamber of the pump. The re-

filling part of the cycle is now completed and the pump D is in readiness to resume the withdrawal of liquid from the lower chamber B, as previously described.

5 The pipe O, in addition to permitting air to escape from the chamber B into the chamber A during the operation of filling the chamber B, performs another function, i. e., it prevents the liquid in the apparatus being 10 siphoned out of same back to the source of supply. In the event of air entering the apparatus, due to leakage of the valve G or from any other cause, while the pump is not in motion, said air would rise or ascend into 15 the upper part of the chamber A, and thence pass into the pump outlet E and a small quantity of the liquid in the supply line I would flow by gravity to the pool or well L. But when a quantity of air or gas sufficient to 20 fill the pump outlet E to the point where the pipe O is connected to the same has entered, then the return flow of liquid from the chambers A and B back to the source of supply will be effectively prevented and the incoming air flowing directly through the pipe O 25 into the horizontal portion I' of the supply line.

Second and subsequent cycles

30 At the beginning of the second cycle, the chamber B, receptacle K, pump inlet pipe C, part of the vertical portion I² of the supply line, the pipes R and M and a part of the pipe S are filled with liquid, and the upper 35 portion of the chamber A, pump outlet pipe E and the portion of the discharge line F below the check valve G contain the gas or air which had previously been expelled from the chamber B, receptacle K, pipe M, pump 40 inlet pipe C, vertical portion I² of the supply line and the pipe S during the operation of filling the lower chamber B with liquid. At this time the chamber A contains sufficient liquid to seal the upper end of the pipe R, 45 where it enters said chamber. During this second cycle the pump D draws the charge of liquid from the chamber B through the pump inlet C and delivers said charge through the pump outlet E into the upper 50 part of the chamber A, gradually compressing the air or gas in the upper part of the chamber A to a pressure sufficient to overcome the pressure in the portion of the discharge pipe F beyond the check valve G, 55 thereby causing said check valve to open and permit the compressed air or gas to escape through the discharge pipe F. The passage of any gas or air from the upper part of the chamber A or from the pump outlet E into 60 the chamber B through the pipe O is effectively prevented by reason of the fact that the end of the pipe O which communicates with the pump outlet E is then flooded or sealed by the liquid that is escaping through the pump outlet E into the chamber A dur-

ing this period, i. e., while the pump D is withdrawing the charge of liquid from the chamber B and delivering said charge to the chamber A. The discharge of liquid from the pump D into the chamber A continues 70 until the receptacle K has been completely emptied of liquid, whereupon the discharge of the liquid from the pump will be interrupted by reason of the air or gas which entered the chamber B during the pumping 75 interval, escaping from said chamber through the receptacle K and pipe M into the pump inlet pipe C. The flow of liquid through the pump outlet E having ceased, the pipe O now being open or unsealed and the check valve G now being closed, the air or gas pressure in the chambers A and B and in the connecting ducts becomes equalized, thus completing the second cycle. 80 Upon the completion of this second cycle the liquid in the supply line I will have ascended to a greater height than it had attained at the end of the first cycle, the level at which the liquid now stands in the supply line being 85 dependent upon the difference in the pressures in the chamber B and at the surface of the pool or well L, in which the inlet end of the supply line I is submerged. 90

After practically all of the air or gas originally contained in the supply line I has 95 been exhausted by repeated cycles of pumping and refilling, as above described, or after the pressure difference between the chamber B and pool L has reached such a degree as to cause a continuous column of liquid to be 100 established between the pool L and the impeller chamber of the pump, a quantity of liquid will flow continuously from the horizontal portion I' of the supply line, through the pipe S, into the pipe M, thereby keeping 105 said pipe M filled with liquid, and thus preventing air or gas, which may be in the upper part of the chamber B from escaping from said chamber and passing into the pump inlet pipe C through the receptacle K and 110 pipe M.

If the level of the liquid in the pool L recedes, during the operation of drawing liquid out of said pool, or if the vertical distance between the horizontal portion I' of the supply line and the level of the liquid in the pool L is increased, or if air or gas enters the upper portion of the supply line or the upper portion of the chamber B, to such an extent or degree as to cause the flow of the liquid from 115 the pool L through the supply line I into the chamber B to be interrupted, or considerably diminished, then the liquid in the downwardly-inclined pipes M and S will drain out of said pipes into the pump inlet pipe C, due to gravity, and any air or gas in the chamber B will then pass from the upper 120 part of said chamber through the receptacle K and pipe M into the pump inlet pipe C, and thence into the pump D. Said pump 125

will immediately cease delivering liquid to the outlet pipe E, and upon the cessation of the flow of liquid through the outlet pipe E, the check valve G will close and the pipe O will become unsealed, thereby causing the pressures in the chambers A and B to become equalized through the pipe O, as previously described. Thereafter, liquid will return to the chamber B and refill the same through the connection N and pipe R, and the gas or air which had accumulated in the chamber B and receptacle K will pass into the chamber A, as previously described. Subsequently, when the chamber B is emptied or exhausted of liquid, a minus pressure will be again created in said chamber and in the supply line I. Thus cycles will continue until the pressure difference between the chamber B and the surface of the pool L is sufficient to cause a continuity of flow of liquid from the pool L to the chamber B, the number of cycles that the apparatus makes depending upon the length and diameter of the supply line I and upon the vertical distance from the chamber B to the source from which the supply of liquid is drawn.

When this apparatus is used solely as a means of diminishing pressure in a vessel, piping system, or other device, the apparatus will operate in the manner previously described, except that there will be no flow of liquid into the chamber B from the supply line. In such cases the cycles will continue so long as the pump D continues to operate at the proper rate of rotation and the diminution of pressure will continue until the greatest diminution of pressure obtainable with the character and temperature of the liquid contained in the apparatus will have been attained.

The proper functioning of this apparatus is dependent upon the interrupted withdrawal of a predetermined quantity of liquid from the chamber B by the pump D, followed by a period of time during which the pump D remains air or gas bound and does not withdraw liquid, and during this period the lower chamber B is replenished with a charge of liquid preparatory to the subsequent pumping operation of the cycles.

This sequence of functioning and the periodicity are accomplished through receptacle K and pipe M which interpose a measured or specific quantity of liquid between the gas or air in the upper part of the chamber B and the pump intake C for the purpose of preventing said gas or air flowing into pump intake C during the pumping period of the cycles. The cross-sectional area of the outlet of pipe M is so proportioned that the chamber B will be emptied of liquid to the point where the pump inlet pipe C is attached to said chamber before all of the liquid in the receptacle K has escaped from same through the pipe M into the pump inlet pipe C. Dur-

ing the interval in which the liquid in the receptacle K is escaping through the pipe M, the pump inlet pipe C is filled with liquid, and under this condition the liquid then returning to the chamber B through the connection N and pipes R and O passes through the pump and the pump continues to deliver the liquid so returning into the chamber A through the pump outlet E. But when the receptacle K has been emptied of liquid, the air or gas in the upper part of the chamber B passes through the pipe M into the pump inlet C, and thence into the pump D, thus causing the pump to cease delivering liquid and remain in an air bound condition. Said pump will not resume the delivery of liquid through the outlet pipe E until after the chamber B has been again entirely filled with liquid and the receptacle K and pipe M flooded with liquid. When the chamber B, receptacle K and pipe M are filled with liquid, the pump D is again in readiness to resume the delivery of liquid through the pump outlet.

The action of the pipe R which is used to permit a slug of entrapped air to escape from the intake C of the pump is as follows: When the chamber B and receptacle K are entirely filled with liquid, the pump D is still maintained in an air bound condition by a small amount of air or gas being entrapped in the pump inlet C between the rotating element of the pump and the point where the pipe M enters the inlet C, thereby preventing the liquid in the pump inlet C from entering the impeller chamber of the pump. This small slug of air or gas remains entrapped in the upper part of the pump inlet C after the chamber B is entirely filled with liquid, and until the static pressure from the chambers A and B is communicated by reason of the continuity of the body of liquid through the connection N and pump inlet C. When this condition of hydro-static pressure has been established, then the pressure in the pipe R at the point where said pipe is attached to the chamber A rises to a pressure in excess of the static pressure in the chamber A at the point where the pipe R is connected to same. At this moment the hydro-static pressure in the chamber A at the point where the pipe R is connected to same is overcome and the slug of the entrapped air in the upper part of the pump inlet C is suddenly forced upwardly through the pipe R into the chamber A, thereby permitting the liquid in the intake C to enter the impeller chamber of the pump, and thus put said pump in condition to withdraw liquid from the chamber B.

As previously stated, the function of the pipe S is to keep the pipe M flooded with liquid after a continuous column of liquid has been established between the source of supply and the impeller chamber of the pump. The object in flooding the pipe M

under this condition is to prevent air or gas, which may at this time be contained in the upper part of the chamber B, from entering the pump D or the inlet C of said pump, and interfering with the operation of the pump. Said pump will deliver liquid that enters the chamber B through the vertical portion I² of the supply line, even though said chamber B is partly filled with air or gas, and will continue to so deliver liquid under this condition until the chamber B contains air or gas to a point where the pump inlet C is attached to same. When this condition arises and chamber B is exhausted of liquid to the point where the inlet C terminates in said chamber, then a quantity of air will enter the pump D through the inlet C, causing said pump to become air or gas bound. Consequently, the pump D will not deliver liquid, and as the delivery of liquid from said pump ceases, the flow of liquid through the supply line I ceases, and as the flow of liquid in said supply line ceases, the liquid in the pipe S will drain out of same. When said pipe S is drained, the pipe M will likewise drain into the pump inlet C, and at this moment air or gas will pass through the pipe M into the inlet C and pump D, causing the liquid in the inlet C to descend to the level of the liquid in the chamber B.

While the pump D is in operation and is delivering liquid, there is a constant and continuous return of liquid from the chamber A to the chamber B through the connection N and through the pipe O, and there is also a return of liquid through the pipe R from the chamber A into the pump inlet C. After the supply line I has been entirely exhausted of air or gas, and there is a continuous flow of liquid being delivered by the pump D and discharged through the discharge pipe F leading from the chamber A, no purpose is served by the return of liquid through the pipes O and R and connection N, and therefore, this return flow can be prevented by closing the valves O', R' and N'.

The pump described in my said prior patent is required to begin discharging liquid against a pressure greater than the pressure of the liquid at its intake, and the greater this pressure difference, the longer is the time interval required to expel any air or gas which had become entrapped within the pump's impeller or impeller chamber, the expulsion of this air or gas being a pre-requisite to the proper functioning of the pump. In my present pump there exists no pressure difference between that at the pump's intake and that at which the pump is required to begin discharging liquid, and therefore, the period of time required for expelling any entrapped air or gas from the pump's impeller or chamber is materially reduced.

Having thus described my invention, what

I claim as new and desire to secure by Letters Patent is:

1. A pump priming mechanism, comprising a chamber that is adapted to hold a charge of liquid, a supply line or suction line leading to said chamber, a pump for withdrawing the charge of liquid from said chamber so as to create a minus pressure in same, means for supplying another charge of liquid to said chamber, and a connection between the intake of the pump and said chamber that is adapted to hold liquid which is supplied to the pump intake by gravity simultaneously with the operation of withdrawing a charge of liquid from said chamber. 70

2. A pump priming mechanism, comprising a chamber that is adapted to hold a charge of liquid, a supply line or suction line leading to said chamber, a pump for withdrawing the charge of liquid from said chamber so as to create a minus pressure in same, means for supplying another charge of liquid to said chamber, and a connection between the intake of the pump and said chamber that is adapted to hold liquid which is supplied to the pump intake by gravity simultaneously with the operation of withdrawing a charge of liquid from said chamber, said connection being so constructed and arranged that it will supply sufficient air to the intake of the pump to insure the pump remaining in an air bound condition during the operation of filling said chamber with liquid. 85

3. A pump priming mechanism, comprising a chamber that is adapted to hold a charge of liquid, a supply line or suction line leading to said chamber, a pump for withdrawing the charge of liquid from said chamber so as to create a minus pressure in same, means for supplying another charge of liquid to said chamber, and a connection between the intake of the pump and the upper portion of said chamber that comprises a receptacle adapted to hold a liquid and arranged so that the liquid in said receptacle will pass into the pump intake by gravity simultaneously with the operation of withdrawing the charge of liquid from said chamber. 100

4. A pump priming mechanism, comprising a chamber that is adapted to hold a charge of liquid, a suction line or vacuum line leading to said chamber, a pump for withdrawing the charge of liquid from said chamber so as to create a minus pressure in same, means for replenishing the charge of liquid in said chamber, and means connected to the top side of the intake of the pump for permitting air that becomes trapped in said intake during the operation of filling said chamber with liquid to escape from said intake, thereby insuring the liquid in the intake passing into the chamber of the pump. 115

5. A pump priming mechanism, comprising two chambers arranged at different levels

and adapted to hold a liquid, a suction line or vacuum line leading to the lower chamber, a pump of the rotary type having its intake communicating with the lower chamber and its outlet communicating with the upper chamber for withdrawing a charge of liquid from the lower chamber and forcing said charge into the upper chamber, means for permitting liquid to pass from the upper chamber into the lower chamber, and a passageway leading from the top side of the inlet of the pump and connected to the upper chamber at a point below the level of the liquid in said chamber for permitting a slug of entrapped air in the intake of the pump to escape from same in the operation of filling the lower chamber.

6. A pump priming mechanism, comprising two chambers arranged at different levels and adapted to hold a liquid, a suction line or vacuum line leading to the lower chamber, a pump of the rotary type arranged with its inlet communicating with the lower chamber and its outlet communicating with the upper chamber for withdrawing a charge of liquid from the lower chamber and forcing said charge into the upper chamber, means for permitting the liquid to pass from the upper chamber into the lower chamber, a connection between the intake of the pump and the upper portion of said lower chamber arranged so as to supply liquid to said intake during the operation of withdrawing the charge from the lower chamber and to supply air to said intake during the operation of filling the lower chamber, and a passageway leading from the pump intake to the upper chamber for permitting entrapped air to escape from said intake under certain conditions.

40. 7. A pump priming mechanism, comprising a chamber that is adapted to hold liquid, a pump of the rotary type communicating with said chamber, a suction line leading to said chamber from a source of liquid supply, and a passageway or conduit leading from the suction line and attached to the pump intake at a point between said chamber and the impeller chamber of the pump for continuously supplying liquid to said intake after a continuous column of liquid has been established between the source of supply and the impeller chamber of the pump.

8. A pump priming mechanism, comprising two chambers arranged at different levels and adapted to hold a liquid, a suction line that leads to said lower chamber, a pump of the rotary type arranged with its intake communicating with the lower chamber and its outlet communicating with the upper chamber for drawing a charge of liquid from said lower chamber and forcing said charge into the upper chamber, means for permitting liquid to pass from the upper chamber into the lower chamber to form a charge in said lower chamber, a discharge pipe leading

from the upper chamber and equipped with a check valve, and a connection between the outlet of the pump and said suction line arranged at a higher elevation than the liquid level in the upper chamber and constructed so as to permit air to pass from the lower chamber into the upper chamber and also to admit air to the suction line to prevent siphoning.

9. A pump priming mechanism, comprising two chambers arranged at different levels and adapted to hold a liquid, a suction line that leads to said lower chamber, a pump of the rotary type arranged with its intake communicating with the lower chamber and its outlet communicating with the upper chamber for drawing a charge of liquid from said lower chamber and forcing said charge into the upper chamber, means for permitting liquid to pass from the upper chamber into the lower chamber to form a charge in said lower chamber, a discharge pipe leading from the upper chamber and equipped with a check valve, and a connection between the pump outlet and said suction line constructed and arranged so that said connection will be water sealed when liquid is being delivered by the pump to the upper chamber and will be unsealed at all other times.

10. A pump priming mechanism, comprising two chambers arranged at different levels and adapted to hold a liquid, a suction line leading to said lower chamber, a discharge line leading from the upper chamber and equipped with a check valve, a pump of the rotary type for withdrawing liquid from the lower chamber and introducing said liquid into the upper chamber, means for permitting a charge of liquid to pass from the upper chamber into the lower chamber and into the intake of the pump, means for permitting the air displaced from the lower chamber and the pump intake during the operation of filling the same to enter the upper chamber, and a connection between the pump intake and the upper portion of the lower chamber arranged so as to form a self-draining passageway through which air can pass from the lower chamber into the pump intake and thus maintain the pump in an air bound condition during the operation of supplying a charge of liquid to the lower chamber.

11. A pump priming mechanism, comprising two chambers arranged at different levels and adapted to hold a liquid, a suction line leading to said lower chamber, a discharge line leading from the upper chamber and equipped with a check valve, a pump of the rotary type for withdrawing liquid from the lower chamber and introducing said liquid into the upper chamber, means for permitting a charge of liquid to pass from the upper chamber into the lower chamber and into the intake of the pump, means for permitting

the air displaced from the lower chamber and the pump intake during the operation of filling the same to enter the upper chamber, a connection between the pump intake and the upper portion of the lower chamber arranged so as to form a self-draining passageway through which air can pass from the lower chamber into the pump intake and thus maintain the pump in an air bound condition during the operation of supplying a charge of liquid to the lower chamber, a conduit leading from the pump intake and attached to said upper chamber at a point below the liquid level in said chamber for permitting a slug of trapped air to escape from the pump intake, a conduit leading from the suction line and attached to the pump intake for continuously supplying liquid to the same after a continuous column of liquid has been established between the pump and the source of liquid supply, a conduit attached to the suction line at a point above the level of the liquid in the upper chamber and having an inlet end which terminates at such a point in the outlet of the pump that said inlet end will be sealed against the passageway of air when liquid is flowing from the pump into the upper chamber.

CHARLES S. LEWIS.

12. A pump priming mechanism, comprising two chambers arranged at different levels and adapted to hold a liquid, a suction line leading to said lower chamber, a discharge line leading from the upper chamber and equipped with a check valve, a pump of the rotary type for withdrawing liquid from the lower chamber and introducing said liquid into the upper chamber, means for permitting a charge of liquid to pass from the upper chamber into the lower chamber and into the intake of the pump, means for permitting the air displaced from the lower chamber and the pump intake during the operation of filling the same to enter the upper chamber, and a passageway between the intake of the pump and said chamber having provision for maintaining a body of liquid between the air in said chamber and the liquid in said intake during a certain portion of the cycle of operations of the mechanism.

13. A pump priming mechanism, comprising two chambers arranged at different levels and adapted to hold a liquid, a suction line leading to said lower chamber, a discharge line leading from the upper chamber and equipped with a check valve, a pump of the rotary type for withdrawing liquid from the lower chamber and introducing said liquid into the upper chamber, means for permitting a charge of liquid to pass from the upper chamber into the lower chamber and into the intake of the pump, means for permitting the air displaced from the lower chamber and the pump intake during the operation of filling the same to enter the upper chamber, a connection between the pump intake and the upper portion of the lower chamber arranged so as to form a self-draining passageway through which air can pass from the lower chamber into the pump intake and thus maintain the pump in an air bound condition during the operation of supplying a charge of liquid to the lower chamber, a conduit lead-

ing from the pump intake and attached to said upper chamber at a point below the liquid level in said chamber for permitting a slug of trapped air to escape from the pump intake, a conduit leading from the suction line and attached to the pump intake for continuously supplying liquid to the same after a continuous column of liquid has been established between the pump and the source of liquid supply, a conduit attached to the suction line at a point above the level of the liquid in the upper chamber and having an inlet end which terminates at such a point in the outlet of the pump that said inlet end will be sealed against the passageway of air when liquid is flowing from the pump into the upper chamber.
